UNITED STATES PATENT OFFICE

GUSTAV EGLOFF, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA

PROCESS FOR CRACKING HYDROCARBONS

Application filed December 4, 1919. Serial No. 342,404.

My invention relates to a process for treating hydrocarbons and refers more particularly to a process for utilizing the heat remaining in pressure distillate bottoms to raise the temperature of the fresh incoming oil charge.

Among its salient objects are to provide a process for a more efficient utilization of the heat generated in oil stills; to provide a process in which the hot pressure distillate bottoms or those which boil above 450° F. instead of being directed from the usual re-run stills to the run down tanks by way of a water condenser are transferred to the charging pipe of a cracking still and there combined, with the raw oil charge; to provide a process in which the pressure distillate bottoms, from the neighboring re-run stills, are collected in a transporting line while they are in a heated condition, as when they come direct from the distilling zone and are pumped back into the raw oil charge about to enter the cracking zone of a still, thereby transferring a portion of their heat to the raw oil and being again subjected with the raw oil to treatment in the cracking tubes; to provide a process in which, besides the feature of utilizing to a greater extent the heat generated, the hot pressure distillate bottoms are more completely cracked by being retreated in the same or a related still as they are combined with the raw oil charge of said still; to provide a novel type of apparatus for carrying out this process and in general to provide a process and apparatus of the character referred to.

In the drawing I have shown a side elevation of a still, partly in section and with parts broken away, showing the double pump arrangement combining the pressure distillate bottoms from neighboring re-run stills with the raw oil.

Referring more particularly to the drawing, within the still 1, consisting of a furnace portion 2 heated by suitable burner 3, are mounted cracking tubes 4 situated above the furnace and receiving the raw oil charge through charging pipe 5 and mixing chamber 6. The charging pipe is controlled by valve 7 and is provided with a suitable pump

26a. The oil vapors after being cracked in the tubes 4 rise through pipe 5 into a vertical tube considered as a whole 8, which consists in a dephlegmator or separator portion 9 and a lower expansion or vapor chamber 10. The oil vapors rising into the expansion chamber are distributed therein by a baffle cone 11. The heavier residue is drawn off from the bottom of the vapor chamber through a pipe 12 controlled by valve 13. 60 The lighter vapors rising in the separator portion are directed through the gooseneck 14 to the pipe coil 15 in the water condenser 16. This condenser is mounted upon any suitable standard 17. The distillate from the condenser passes to the receiver 18 through pipe 19. A drawoff 20 controlled by valve 21 provides a means of taking off the distillate from time to time. A suitable gauge 22 of a common type is mounted on the 70 side of the receiver and denotes the quantity of distillate in the receiver. A pressure gauge 23 registers the pressure upon the system. A pressure valve 24, together with the draw-off valve 21 and the valve 13 in the residuum 75 line provide a means of regulating the pressure in the system.

My invention consists in introducing pressure distillates or pressure distillate bottoms from any source, preferably neighboring stills, while the bottoms are yet in a heated condition and before they are allowed to cool or before they have been passed through water or aerial coolers, through a charging pipe 25, a suitable charging pump 26 and a pipe 85 line 27, which charges the pressure distillate bottoms directly to the charging line of the still through the mixing chamber 6. The charging pipe 27 may be regulated by the valve 28 and the amount of distillate introduced into the system controlled by this valve. The introduction of these pressure distillate bottoms while in a heated condition, besides the advantage of retreating said distillate bottoms, tends to transfer the heat 90 thereof to the raw oil charge.

It will be seen that this will greatly economize the heat of the still, into which the pressure distillate bottoms are charged. A reflux line 29 is tapped into the lower portion 100

of the separating chamber of the dephlegmator to direct the reflux condensate from the dephlegmator back to the charging line 5 through the mixing chamber 6. This reflux line 29 is controlled by a valve 30.

The following illustrative run may be given: Taking gas oil from the mid-continent field, such as Kansas or Oklahoma yield, say of 32° Baumé; this gas oil is charged into 10 the cracking zone and is heated to a temperature of from 750° to 900° F. A suitable pressure say, from 50 to 150 lbs. is maintained on the system during the entire operation. Gas oil treated in this manner yields 15 from 30% to 40% of gasoline or other low boiling point hydrocarbons having an end point of 400° F.

Whereas, before utilizing the hot pressure distillate bottoms, by charging same mixed 20 with the charging oil into the cracking still, there was consumed per gallon of gasoline made approximately 95,000 B. t. u.; after adding the hot pressure distillate bottoms the B. t. u value per gallon of gasoline dropped 25 to 87,000. In carrying out the foregoing run, I utilize from 10% to 25% hot pressure distillate bottoms, mixed with the gas oil, although a higher percentage of the distillate bottoms may be used. These hot distillate bottoms impart heat to the gas oil and serve to materially lower the quantity of fuel, as well as the time required to crack the oil. By the term "distillate bottoms," it is 30 meant that I utilize that portion of distillate resulting from the cracking of oil which has 35 accumulated in the bottom of a re-run still, and which has a boiling point above 450° F.

In other words, by practicing my process a fuel saving of from five to ten percent in 40 cost per gallon of gasoline may be effected.

I claim as my invention:

A process for converting relatively heavy into relatively lighter hydrocarbon oils comprising initially subjecting the oil to cracking 45 conditions of temperature and pressure while flowing through a heating coil disposed within a furnace, delivering the heated oil from said coil to an enlarged reaction zone from which no unvaporized oil is permitted 50 to return to said heating coil, subjecting vapors issuing from said enlarged reaction zone to reflux condensation, simultaneously introducing to a mixing chamber hot reflux condensate separated from the vapors undergoing 55 reflux condensation, hot pressure distillate bottoms and a quantity of fresh charging oil for the process, and supplying the commingled oils directly from said mixing chamber to said conversion unit.

GUSTAV EGLOFF.
